ATTORNEY

UNITED STATES PATENT OFFICE.

ABRAHAM I. LEVIN, OF FAR ROCKAWAY, NEW YORK.

RIM LINER.

Application filed May 28, 1923. Serial No. 641,806.

To all whom it may concern:

Be it known that I, ABRAHAM I. LEVIN, a citizen of the United States of America, residing at Far Rockaway, Queens County, 5 State of New York, have invented certain new and useful Improvements in Rim Liners, of which the following is a specification.

This invention relates to a rim liner and 10 in particular to one which is used on the outer face of a metal rim felly to afford a protection to the inner tube.

A particular object of the invention is to provide a rubberized fabric strip which may 15 have adhesive qualities and which is used to line the outer periphery of the metallic rim used on pneumatic tire wheels to prevent rusting of the rim.

A further object is to provide a liner of 20 the character described which will adhere to the inner periphery of the tire casing or shoe to close the opening therein, into which the tube has been inserted so that the tube is protected not only from rubbing against 25 the metal rim but also from creeping relatively to the shoe in which it is encased thereby reducing wear of the tube. The adhesive side of the liner may be applied to the rim directly.

30 A further object is to provide a seal for the casing or shoe so that no dirt, grit or rust can obtain access to the tube to cause puncture or wear thereof.

A further object of the invention is to provide a liner which is waterproof, which will 35 protect the tube from rubbing or bearing on the rim which may become rusted after dampness, and which will have a tendency to prevent relative creeping between the 40 shoe and the rim.

A further object is to provide a liner, the 45 ends of which will be vulcanized together by the heat generated in the tire when the wheel is revolving; thus preventing its working 50 loose and consequent dragging from the wheel.

In the drawings wherein one embodiment 55 of my invention is illustrated:—

Fig. 1 is a perspective view of my liner 60 opened out and shows the construction of one end thereof where it passes over the valve stem when applied to a rim, showing also in dotted lines the strip when rolled up.

Fig. 2 is a section through a tire, and rim

therefor showing the position of my rim 55 liner in place, the section being taken to show the valve and relative location of said liner; and,

Fig. 3 is a partial longitudinal section, 60 greatly enlarged through the liner at the end thereof, which fits over the valve stem and shows the construction at that point.

Referring to the drawings in detail, 5 denotes a strip of canvas or other suitable fabric which is impregnated with an upper 65 layer of adhesive material 6. This material is a gummy substance which will adhere to the inner periphery of the shoe or tire casing or to the rim periphery. One end of the strip is faced with a short piece of canvas or suitable fabric 7, as illustrated in Fig. 3, the same extending beyond the opening 8 in the liner. This opening is provided to allow for the passage therethrough of the valve stem 9 which projects from the usual 70 inner tube 10 and through the rim 11.

The facing piece 7 extends beyond the extreme end of the liner and exposes on the under side thereof, a portion of the adhesive surface of said piece 7. In applying the 80 liner the same is passed around the rim of the wheel with the adhesive surface up and the opening 8 therein matching the opening in the rim. The opposite end of the liner which has been brought around the rim is 85 inserted under the overhanging portion of the piece 7 so that the two adhesive surfaces are together, then the tire is put on in the usual manner and the inner periphery of the shoe will rest on the adhesive surface of the 90 liner and will, during the running of the car become very tightly fixed thereto. The heat generated by the running of the car will vulcanize the lower side of the piece 7 to the end of the liner with which it contacts, as explained above, so that the ends of the liner will be bound firmly together and will be prevented from leaving the wheel by accident. It will be further noted that the 95 both sides of the liner or canvas may be provided with the adhesive surface so that the liner will also adhere to the rim as well as the shoe.

This adhesive substance is of a rubbery nature and excludes moisture so that the tire casing or shoe is rendered waterproof by the application of the liner. The canvas backing which is extremely tough takes up the wear which would ordinarily 100 105

occur to the inner tube due to its rubbing on the face of the rim.

It will therefore be seen that I have provided a liner which will prevent dust and grit from entering the tire casing. It will lessen the liability of puncturing the inner tube.

It is to be understood that the liner may be applied with the adhesive side against the rim periphery, thereby preventing moisture from getting to the rim and rusting

same, which usually causes excess wear and puncture of the inner tube.

What I desire to secure by Letters Patent is:—

A rim liner consisting of a fabric band, adapted to be placed around the rim of a wheel, the ends of said band being adapted to be joined and held together by an adhesive substance, and one of said ends being reinforced.

ABRAHAM I. LEVIN.
